DOLPH A. PAGE, OF KEENE, NEW HAMPSHIRE.

COASTING-SLED.

977,749.

Specification of Letters Patent.

Patented Dec. 6, 1910.

Application filed March 14, 1910. Serial No. 549,139.

To all whom it may concern:

Be it known that I, DOLPH A. PAGE, a subject of the King of Great Britain, residing at Keene, in the county of Cheshire and 5 State of New Hampshire, have invented a new and useful Coasting-Sled, of which the following is a specification.

My invention relates to improvements in sleds, more particularly coasting-sleds, and 10 resides in certain peculiar general features of construction in which are included a guiding or steering mechanism, all as herein-after set forth.

The object of my invention is to produce 15 a strong, durable, and comparatively simple and inexpensive coasting-sled, which can be easily and conveniently guided without the use of the feet.

A further object is to provide a sled of 20 this kind that can be steered with a wheel, or with a rope, or by direct application of the hands to the steering runner, such wheel with its directly connected and associated parts being detachable and removable so as 25 to be entirely out of the way when it is desired to resort to either of the other two steering methods. The removal of the steering-wheel apparatus can be easily and quickly effected, and the same thing is true 30 in regard to the replacing of the same.

Other objects will appear in the course of the following description.

I attain these objects by the means illustrated in the accompanying drawings, in 35 which—

Figure 1 is a top plan of a coasting-sled which embodies my invention in a practical form; Fig. 2, a side elevation of such sled; Fig. 3, a bottom plan of a portion of the 40 sled, showing the equalizing springs in full; Fig. 4, a central, longitudinal, vertical section through said sled, the rear portion being broken off; Fig. 5, a transverse, vertical section taken on the axial line of the steering 45 apparatus and looking toward the front end of the sled, the steering-post being in elevation, and, Fig. 6, a front end elevation of the steering-fork-arm.

Similar figures refer to similar parts 50 throughout the several views.

My invention is applicable to a sled which consists of a seat mounted on two runners and provided with a third runner for guiding or steering purposes, and I have shown 55 such a sled in the drawings, wherein 1 represents the seat, 2—2 represent the main run-

ners, and 3 represents the steering runner. The runners 2 are rigidly connected by means of two cross-pieces 4 and 5, and the seat 1 is fastened in place on said cross-pieces. These members in and by themselves are old and well-known. 60

The steering runner 3 is pivoted at 6 to the cross-piece 5, such pivot, in the present case, passing downward through the seat 1 and the center of said cross-piece into said runner some little distance from the back end thereof. The runner 3 is cut away at 7 to receive the cross-piece 5 and so that said runner can swing to whatever extent may be 70 necessary without interference on the part of said cross-piece. The seat 1 and the cross-piece 5 bear directly on the runner 3, and a cross-bar 8, which forms a foot-rest and is rigidly connected with the overhanging 75 front terminals of the main runners 2, also bears on said runner 3. In this way the runner 3 supports the front part of the sled, yet said runner may be freely turned either to the right or to the left in spite of the frictional engagement at the three points noted, because the members are so proportioned 80 that the sled supports and carries its load rather well back of the aforesaid points and very largely, chiefly in fact, on the main 85 runners 2.

In order to maintain the runner 3 normally in parallelism with the runners 2, two equalizing springs 9 are employed. These springs are introduced between opposite 90 sides of the runner 3 and the runners 2, being located just in front of the forward end of the cut-away portion 7 or a little in advance of the cross-piece 5, and having their ends fastened in any suitable manner to the 95 runners. These springs, while strong enough to swing the runner 3 into coincidence with the central, longitudinal, vertical plane of the sled, when diverted from such plane and upon being released from the 100 diverting force, and to retain it in such plane, under ordinary or normal conditions, are not so stiff as to materially interfere with the proper operation of said runner incident to the act of steering. 105

The steering runner 3 extends upward in front of the cross-bar 8, and projecting from opposite sides of this upwardly-extending part are two screw-eyes 10 to which the ends of a rope 11 may be attached. Mounted on 110 the cross-bar 8 is a guide 12 for the rope 11 which passes from the screw-eyes 10 back-

ward through openings or notches 13 in the ends of said guide.

The front ends of the runners 2 are provided with screw-eyes 14—14 for the attachment of a rope that may be used in drawing the sled. Ordinarily the rope 11 will be attached to the screw-eyes 10 and employed for draft as well as steering-purposes, but this or another rope may be attached to the screw-eyes 14 and used as the draft rope, if desired.

The before-mentioned steering-wheel apparatus consists of a steering-wheel 15, a vertical steering-post 16 to the top of which said wheel is fixed, a horizontal fork-arm 17 so connected with said post that said arm moves with said post, a cross-bar 18 secured to the sled frame, and a pivot 19 which permits the steering-post to turn with its arm. The cross-bar 18 extends across the top of the sled, over the cross-piece 5, and is fastened to the upper edges of the runners 2 by means of two screw-eyes 20; or in any other suitable manner which permits said cross-bar to be removed readily. The steering-post 16 has its base mortised into the fork-arm 17 near the back end of the latter, but this particular method of providing a rigid connection between the two members is not important. The pivot 19 extends upward through the center of the cross-bar 18 into the steering-post, coinciding with the axis of said post and constituting the real axis thereof. The location and arrangement of the parts are such, by preference, that the pivot 19 is directly above the pivot 6.

The fork-arm 17 rests at its rear terminal, with the steering-post 16, on the cross-bar 18, and said arm projects forward from said cross-bar to rest on the upper edge of the runner 3, being augmented in depth at the front end, as clearly shown in Fig. 4, for that purpose; in other words, said fork-arm is supported in a horizontal position on said cross-bar and said runner. Depending from the front end of the fork-arm 17, and adapted to receive between them and snugly embrace a portion of the runner 3, are two lugs 21. These lugs form the fork of the arm 17, and by reason of their engagement with the runner 3 carry said runner with said arm when the latter is swung about the pivot 19, the runner, of course, swinging about its pivot 6.

Assuming that the steering-post apparatus just described is in place, it is clear that, when the steering-wheel 15 is turned in either direction, the steering runner 3 must also be turned in the same direction, since the steering-post 16 then makes a partial revolution on its pivot 19 and carries with it the fork-arm 17 and the latter imparts its movement to said runner. The springs 9 tend to steady the action of the steering-wheel apparatus and to restore the runner

3 to normal position upon the release of the steering-wheel. Said steering-wheel is situated in a suitable and convenient position and at a suitable and convenient height, so that the mechanism controlled thereby can be operated to the best advantage, the operator being seated on the sled behind the steering-post with his feet on the foot-rest. When thus seated the operator can also steer by means of the rope 11, regardless of the presence or absence of the steering-wheel apparatus, the method of so steering being obvious.

When the steering-wheel apparatus is not required it can be removed from the sled after first taking out the screw-eyes 20. The absence of such apparatus does not affect the steering runner in any way. With the aforesaid apparatus out of the way a person can lie at length on the sled and steer the same by grasping with his hands the runner 3 and swinging said runner on its pivot 6 in whatever direction or directions may be necessary. The springs act in the same way in throwing the runner 3 into parallelism with the runners 2 and retaining it in such relationship with said runners 2 whether the steering is accomplished directly by hand or through the medium of the rope 11, as when by means of the steering-wheel apparatus. It is self-evident how the sled is guided and its direction changed by the steering runner and the manipulation thereof.

That this sled is susceptible to change, not only in matters of shape and size but also of construction of some or all of its parts, is evident, therefore I do not desire or intend to be restricted in these particulars beyond the restrictions imposed by my claims.

What I claim as my invention, and desire to secure by Letters Patent, is—

1. In combination with the frame of a sled, including the main runners, the seat, and a foot-rest cross-bar located forward of said seat and connecting the front ends of said runners, of a central steering runner at the forward end of the sled, said steering runner being pivoted directly to said frame beneath the same and arranged in direct supporting and contacting relation to said cross-bar and to other parts of the frame behind such bar.

2. The combination, in a sled, of the frame, including the main runners, of the sled, a cross-bar and a guide mounted at the front end of said frame on said runners, said guide having its ends adapted to support a rope, a central steering runner pivotally connected with said frame and extending beneath and in contact with said cross-bar and forward of said guide, and a rope attached to the forwardly-extending part of said steering runner and passing outwardly and rearwardly to the aforesaid

ends of said guide and behind the same, such rope being in sliding relation with said guide.

3. The combination, in a sled, with the frame, including the main runners, of the sled, and a centrally-located steering runner, for the forward end of the sled, pivotally connected with said frame, of a steering-post pivotally mounted on the sled and provided with a forwardly-extending arm arranged in direct engagement with said steering runner to operate the same when said post is operated, the steering-post pivotal connection being independent of the steering runner pivotal connection but having its axial center coincident with the axial center of said last-mentioned pivotal connection.

4. The combination, in a sled, with the frame, including the main runners, of the sled, and a centrally-located steering runner, for the forward end of the sled, pivotally connected with said frame, of a removable

member mounted on the sled, and a steering-post pivotally mounted on said removable member and provided with a forwardly-extending arm arranged in direct engaging relation with said steering runner to operate the same when said post is operated.

5. The combination, in a sled, with the frame, including the main runners, of the sled, a centrally-located steering runner, for the forward end of the sled, pivotally connected with said frame, and equalizing springs interposed between said main runners and said steering runner, of a steering-post pivotally mounted on the sled and provided with a forwardly-extending arm arranged to engage said steering-runner and to operate the same when said post is operated.
